CAR COUPLER

Hugh A. Macnaghie, Herrin, Ill.

Application March 15, 1934, Serial No. 715,747

2 Claims. (Cl. 213—188)

This invention relates to improvements in car couplers and pertains particularly to a coupler which is designed particularly for use upon mine cars.

5 The primary object of the present invention is to provide a car coupling of an improved character which may be so easily and quickly manipulated for coupling and uncoupling cars that the time consumed for this operation may be greatly 10 decreased from the time required at present, thus making it possible to generally increase the production speed of mines where the couplers are used.

Another object of the invention is to provide 15 an improved coupler having a novel type of head and link unit in which the link will automatically connect itself with the head when the two units are brought together.

Other objects and advantages of the invention 20 will become apparent as the description of the same proceeds and the invention will be best understood from a consideration of the following detailed description taken in connection with the accompanying drawings forming part of this specification, with the understanding, however, that the invention is not confined to any strict conformity with the showing of the drawings but 25 may be changed or modified so long as such changes or modifications mark no material departure from the salient features of the invention as expressed in the appended claims.

In the drawings:—

Figure 1 is a view partly in longitudinal section and partly in elevation of a complete coupler constructed in accordance with the present 35 invention;

Figure 2 is a sectional view taken substantially upon the line 2—2 of Figure 1;

Figure 3 is a view in front elevation of the head 40 unit;

Figure 4 is a view in top plan of the complete link unit showing the resilient bumpers associated therewith;

Figure 5 is a sectional view taken upon the line 45 5—5 of Figure 4.

Referring now more particularly to the drawings wherein like numerals of reference indicate corresponding parts throughout the several views, the numeral 1 indicates generally the head unit 50 while the link unit is indicated as a whole by the numeral 2.

The head unit comprises a body portion 3 which is preferably in the form of a substantially rectangular block from the rear side of which projects the spring encircled stem 4 while the front

wall 5 of the block has its upper edge undercut to form the inwardly inclined face 6, and from the bottom edge the front wall curves upward and inward to form the cam surface 7 on which an element of the link unit rides when the units are moved into connected relation.

The central part of the front of the head 3 is cut inwardly to provide the mouth 8 which leads into the chamber 9, the upwardly and inwardly curving surface 7 leading directly into the mouth 10 as illustrated in Figure 1. The bottom of the mouth is formed to provide the flat surface 10 and at the rear of this flat surface there is formed the downwardly extending passage 11 which opens through the bottom of the head body. 15 Directly above this passage 11 is an upwardly opening passage 12 which is of greater cross sectional dimensions than the passage 11 and this leads through the shoulder 13 which is formed upon the top of the head.

Reciprocably mounted in the upper vertical passage 12 of the head is the heavy coupling pin 14, the lower end of which is flat to rest upon the bottom wall 10 of the mouth and in addition, there is formed integrally with the lower end of this pin, the longitudinally extending finger 15 which positions in the passage 11. This finger 15 resists any tendency of the lower end of the pin 14 to swing, particularly if the lower part of the passage 12 becomes enlarged through wear.

The front face of the pin 14 is arcuate longitudinally of the pin as indicated at 16, the curve of this arcuate face starting at the bottom of the pin and merging into the straight front face of the upper portion thereof. The curved faces 7 and 16 thus come together to form a V in which the sides are bowed inwardly as is clearly shown in Figure 1.

The pin 14 has formed therethrough a longitudinally extending slot 17 and extending transversely of the passage 12 and suspended at its ends in the opposite walls of the boss 13 is a movement limiting pin 18 which extends through the slot 17 and thus prevents the complete withdrawal of the coupling pin 14.

The upper end of the coupling pin is provided with a collar 19 which rests upon the boss 13 when the coupling pin is in operative position and there is also connected with the upper end of the coupling pin the ring 20 by which a securing chain may be attached thereto.

The link unit 2 comprises a hanger yoke 21 which is secured by means of the cross plate 22 to a suitable supporting unit of the car and extending through this yoke is a draw bar 23 which

is limited in its longitudinal movement in both directions by the front and rear springs indicated respectively by the numerals 24 and 25. The front end of the draw bar 23 is transversely slotted as indicated at 26 and in this slot is located the apertured tongue 27 which forms an integral part with the body 28. This body has parallel flat sides 29 which are normally vertically disposed and is transversely apertured to receive a pivot pin 30.

At its rear the body 28 has the laterally extending wings 31, the forward faces of which are divided into the two surfaces 32 and 33 which are disposed at an oblique angle and each of which is inclined rearwardly toward the end of the unit carrying the tongue 27.

The tongue 27 is pivotally attached to the bar 23 by means of the pin 34 and at the forward end of the body 28 the pin 30 extends through and pivotally connects with the body the enlarged apertured rear ends 35 of a substantially U-shaped connecting unit 36, the yoke portion 37 of which is apertured to receive the headed pin 38 which forms an integral part of the coupling ring 39.

As will be readily apparent from the foregoing the coupling of the units 1 and 2 is effected by moving the cars carrying the same together so that the ring 39 will ride upon the lower lip 30 into the crotch of the V formed by this surface with the arcuate surface 16 of the coupling pin and through contact with the latter surface cause the coupling pin to shift vertically so that the ring may move into the chamber 9. The coupling pin will then, of course, drop back through the ring and the connection of the units will be completed.

In Figure 4 the same draw bar structure is illustrated as is shown in Figure 1 and as will be here seen the rear spring 25 is secured in place by the washers 40 and nut 41 which is threaded onto the bar and may be adjusted as desired to control the tension of the springs. This nut is not illustrated in Figure 1.

In this view, however, the body 28 is shown with a different type of coupling pin engaging element attached thereto in place of the ring 39 illustrated in Figures 1 and 2. In this form of coupling element there is provided in the place of the U-shaped member 36 the relatively long U-shaped member 42, the rear ends of which are enlarged and apertured as at 43 to receive the pin 30. The forward end of this member 42 has a cross connecting link 44 which cooperates with the yoke portion to provide the ring 45.

In both the member 36 and the U-shaped member 42 the portions 35 and 43 have tangentially formed faces 46 and 47 respectively which

engage the surfaces 33 of the adjacent ears when the link units are disconnected from the head units, so as to maintain these portions of the link units in a substantially horizontal plane, thus making it unnecessary for the workman in charge of the coupling and uncoupling operations to hold the movable portion of the unit 2 in the proper position for entry into the mouth of the coupling unit 1.

The average number of cars coupled by one man in an eight hour working period is 1152 or one every 25 seconds, there being changed from 100 to 150 cars per loading machine unit. Taking an average of 125 and 25 seconds to effect the manipulation of the coupling gives roughly fifty minutes for handling one unit. At this rate 10 loading machines averaging 1250 cars may be handled in approximately eight hours and twenty minutes, thus increasing the number over the present average by about 100.

Having thus described the invention, what is claimed is:—

1. In a coupling, a coupling link comprising a bar member, a head pivotally attached to the bar member and having two parallel faces, a laterally extending ear integral with said head at the rear of each of said side faces, each of said ears having a downwardly facing forwardly and rearwardly inclined surface, a substantially U-shaped element having two side leg portions and a cross connecting portion, said head being disposed between said side leg portions, each of the leg portions of said U-shaped member having a contact face adapted to engage the adjacent inclined surface of the adjacent ear, a pivot pin extending through said leg portions and said head, and means at the forward ends of said U-shaped member for receiving a coupling pin.

2. In a coupling designed to receive a coupling pin, a coupling link comprising a bar member mounted for reciprocal movement, resilient means at opposite sides of the mounting for said reciprocal bar for limiting the movement of the latter, a body pivotally attached to the forward end of said bar, a pair of ear members carried by said body and extending from opposite faces thereof, an element having two side members each having a free end, between which ends said body is received, a pivotal connection between the said last body and the side members of said element permitting the latter to swing in a vertical plane, and means at the forward end of said element for receiving said coupling pin, the said ends of the element being adapted to engage said ears to maintain the element in a predetermined position.

HUGH A. MACONAGHIE.
